UNITED STATES PATENT OFFICE.

HUGO DAHMS, OF BERLIN, GERMANY.

STOCKING-SUSPENDER.

No. 901,155.

Specification of Letters Patent.

Patented Oct. 13, 1908.

Application filed January 20, 1908. Serial No. 411,796.

To all whom it may concern:

Be it known that I, HUGO DAHMS, exporter, a subject of the King of England, and resident of Berlin W. 30, Germany, have invented an Improved Stocking-Suspender, of which the following is a specification.

Stocking suspenders are known in which the edge of the stocking is gripped by a spring clamp. This clamp does not hold unless it is continually tensioned, but as this is not always the case, the stocking is often released.

Stocking suspenders are also known constructed of two loops which are slipped over one another, but these will not last as the fabric soon wears out.

The present invention differs from previous inventions in that a part of the stocking is placed over a ball at the back of which a loop is drawn together so that the stocking cannot be released.

In the accompanying drawing:—Figure 1 is a front view of the suspender. Fig. 2 is a side view thereof, and Fig. 3 shows the suspender in use.

To a band *b* which is fastened to the corset or the like, is sewn a string *g*, which at its lowest end is provided with a button or the like. This button is attached thereto in that the middle of the string is passed through a hole in the button, and then passing the ends of the string which have not yet been sewn to the band *b*, through the loop which is thus formed and then tightening the string, so that the button is held in the loop. To the band *b* is attached a second string *i* which is at its end provided with an eye so that it can be formed into a loop *h* which can be passed over the button *f*.

For attaching the stocking, the upper end *a* thereof is placed over the button or the like *f*, then the loop *h* is drawn over the button and tightened. (Fig. 2). The stocking cannot be released on account of the double pull.

In order to prevent the loop *h* after it has been tightened from loosening, an india-rubber ring *k* or the like is provided on the string *i*, said ring *k* fitting tightly around the string *i*.

Having fully described my invention, what I claim and desire to secure by Lett. Patent is:—

1. A stocking suspender, comprising in combination, a band, a string sewn to the band, a button at the end of the string, a second string attached to said band, an eye at the end of said second string, a loop formed at the end of said second string, said loop adapted to fit over the button, substantially as described and shown and for the purpose set forth.

2. A stocking suspender, comprising in combination, a band, a string sewn to said band, a button at the end of said string, a second string attached to said band having an eye at the end thereof, an india rubber ring around said second string, a loop formed at the end of said second string, said loop adapted to fit over the button, substantially as described and shown and for the purpose set forth.

In testimony whereof I have hereunto set my hand in the presence of two subscribing witnesses.

HUGO DAHMS.
